UNITED STATES PATENT OFFICE.

EDWIN F. JONES AND JOHN A. AULD, OF ERIE, PENNSYLVANIA.

MATERIAL-HANDLING APPARATUS.

Application filed March 31, 1923. Serial No. 629,070.

To all whom it may concern:

Be it known that we, EDWIN F. JONES and JOHN A. AULD, citizens of the United States, residing at Erie, in the county of Erie and State of Pennsylvania, have invented new and useful Improvements in Material-Handling Apparatus, of which the following is a specification.

This apparatus is particularly designed for measuring materials, such as road-making materials where an accurate amount is required. The desirable way of measuring such material is by filling the measuring bin with slightly more than the exact amount and striking off the excess. Heretofore this excess as it was struck off has been allowed to fall and accumulating has required handling. With the present device the material struck off by a strike-off blade is caught and delivered to the measuring bin so that there is no after-handling or difficulty encountered in the operating or clogging of the strike off device. In the preferred form the striking off is accomplished with a movable bin operating under a strike off blade. Details and features of the invention will appear from the specification and claims.

The invention is illustrated in the accompanying drawings as follows:

Fig. 1 shows a side elevation.

Fig. 2 an end view.

Fig. 3 an enlarged sectional view showing the details of the strike off mechanism.

1 marks the supporting posts, and 2 and 3 storage bins carried by these posts and the usual frames. These storage bins are designed to hold different materials such as gravel and crushed stone and have the discharge openings 4 and 5 respectively. A car 6 mounted on wheels 7 is arranged under the storage bins, the wheels operating on tracks 8 so that these cars may be moved to effect the striking off operation and carry the material if desired to a more satisfactory or convenient position to dump into the trucks. Measuring bins 9 and 10 are usually arranged in pairs of suitable size. These are closed at the bottom by doors 11 hinged at 12, these doors being connected or operated by a link 13 operated from a common actuating mechanism 14. The car is moved by a cable 15 running around pulleys 16 and 17, the pulleys 17 being carried by a shaft 18. A gear 19 is mounted on the shaft 18 and operates from a pinion 20, the pinion

being operated by means of a crank 21. It will be understood that there are a number of bins and these are adapted to dump what is commonly called a batch into different compartments of the vehicle which is to receive them.

The openings 4 and 5 over each of the measuring bins 9 and 10 are closed by a gate plate 22 and there are as many gate plates as there are bins. These are actuated by levers 23. Upright strike off blades 24 and 25 are arranged adjacent to the openings 4 and 5 and directly over the upper ends of the measuring bins.

Catcher pockets 26 are carried by arms 27, these arms being pivoted at the ends of the bins at 28 so that the catcher pockets are arranged at the sides of these bins. In Fig. 3 the one at the left is shown in a tilting position and the one at the right in the lowered position, the position it assumes in receiving the excess material as it is struck off by the strike off blade. Rollers 29 are mounted on the arms 27 and inclined bars 30 are arranged in the path of the rollers 29 so that as the bins are moved to a position under the openings 4 or 5 the pocket 26 of that bin is tilted as shown at the left of Fig. 3, thus dumping the material which was received by it in the preceding strike off operation into the bin previous to the deposit of the new quantity of material from the storage bin. The pocket then remains in the inclined position until the filling of the measuring bin when the car is again moved to the right as shown in Fig. 3 and as the excess is struck off it is carried into this pocket and held there until the succeeding operation. The excess material at the right will, when the bin 10 is carried under the opening 5, be tilted thus emptying any material in it into the bin 10 previous to the filling from the opening 5. In this way there is no accumulation of this excess and there is a free and accurate action of the strike off mechanism.

What we claim as new is:

1. In a material handling apparatus, the combination of a measuring bin; an upright strike off blade; means for moving the bin and blade relatively to strike off excess material; and a catcher movable relatively to the bin catching the overflow and returning by its movements the same to the bin.
2. In a material handling apparatus, the combination of a measuring bin; an upright

strike off blade; means for moving the bin and blade relatively to strike off excess material; and a tilting catcher actuated with the relative movement of the blade and bin 5 to return the overflow to the bin.

3. In a material handling apparatus, the combination of a measuring bin; a strike off mechanism; a tilting pocket at the side of the bin adapted to catch excess material; 10 and means for actuating the pocket to return the same to the bin.

4. In a material handling apparatus, the combination of a movable measuring bin; a strike off blade operating over the bin; a 15 tilting catcher arranged at the side of the

bin to catch an overflow; and means actuated as the bin is moved for tilting the catcher.

5. In a material handling apparatus, the combination of a movable measuring bin; 20 a strike off blade operating over the bin; a tilting catcher arranged at the side of the bin to catch an overflow; and means actuated as the bin is moved for tilting the catcher comprising inclines operating on the 25 catcher as the bin is moved.

In testimony whereof we have hereunto set our hands.

EDWIN F. JONES.
JOHN A. AULD.
